CLAIM

The ornamental design for an oven heated tray, as shown and described.

DESCRIPTION

FIG. 1 is a top plan view of an oven heated tray showing my new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof; and

FIG. 7 is an enlarged fragmentary cross-sectional view taken on line 7—7 of FIG. 1.

The diamond bosses on the interior bottom of the oven heated tray are continuous over the entire bottom portion within the dot-dash lines shown in FIG. 1.

FIG. 1
